ENGRAVING APPARATUS

Everett J. Cook, Toledo, Ohio, assignor to H. H. Buggie & Company, Toledo, Ohio, a corporation of Ohio

Application September 23, 1937, Serial No. 165,382

37 Claims. (Cl. 51—100)

This invention relates generally to engraving apparatus and refers more particularly to apparatus of this character wherein an engraving tool is controlled by an optical unit including a light sensitive cell.

One of the principal objects of this invention resides in the provision of an engraving machine wherein the operation of the engraver or tool is controlled by a light sensitive cell which, in turn, is rendered conductive and non-conductive by variations in the intensity of light reflected from the character or design to be reproduced on the work by the tool.

Another object of the present invention consists in the provision of adjustable means for not only varying the depth of the engraving, but for also maintaining the depth of the engraving uniform irrespective of tool wear and irregularities in the surface of the work upon which the engraving is reproduced by the tool.

Another advantageous feature of this invention consists in the provision of engraving apparatus rendering it possible to engrave the character or design on surfaces of irregular contour, and to this end means is provided for varying the position of the tool relative to the surface aforesaid of the work in accordance with the contour of the surface to secure a uniform depth of engraving, irrespective of shape of the surface.

A further object of the present invention resides in the provision of an engraving tool movable into and out of engagement with the surface of the work to be engraved by a beam supported for oscillation by means under control of the light sensitive cell and equipped with means for stabilizing the action thereof without increasing the inertia of the same.

Still another object of the present invention resides in the provision of engraving apparatus wherein the model having the design or character to be reproduced thereon is completely scanned by feeding the optical system in one direction relative to the pattern and wherein means is provided for relatively quickly returning the optical system to its initial starting position relative to the pattern.

A further advantageous feature of the present invention consists in providing engraving apparatus wherein the work to be engraved is fed as a unit with the optical system relative to the engraving tool so that the various portions of the surface of the work to be engraved are successively brought into registration with the tool.

A still further feature of this invention resides in the provision of means responsive to the op-

eration of the feeding means in the last preceding paragraph to discontinue the feed when the optical system is at the end of its travel in one direction and automatically initiate the feed when the optical system has been returned to its initial starting position.

A further object of this invention which contributes materially to the accuracy of the engraving consists in means for maintaining the focal distance of the optical unit uniform, irrespective of inaccuracies in the surface of the pattern having the characters or design thereon to be duplicated. The accuracy of the engraving apparatus is further enhanced by providing an arrangement wherein the light reflected from the record or pattern is permitted to diffuse or spread over the cell. By permitting the reflected light to diffuse or spread over the cell, more uniform output of the cell results, irrespective of variations in the sensitivity of the different portions of the light sensitive plate of the cell.

A still further feature of this invention resides in the provision of an engraving machine having provision for rotating the work support and pattern relative to the engraving tool and optical unit at a speed suitable for efficient engraving during the actual cutting operation and at a much faster rate of speed during the intervals the tool is free from cutting engagement with the work. This arrangement is particularly advantageous in cases where only a part of the surface of the work is to be engraved since it eliminates lost motion and renders it possible to appreciably increase production.

In addition to the foregoing, this invention contemplates engraving apparatus rendering it possible and efficient to cut characters or designs in glass articles, such as tumblers of various shapes, and to this end the invention also contemplates improved means for supporting articles of various shapes and sizes relative to the tool.

Aside from the above, the invention contemplates a compact engraving machine having provision for engraving a plurality of articles simultaneously and the manner in which this is accomplished, as well as the foregoing and other objects, will be made more apparent as this description proceeds, especially when considered in connection with the accompanying drawings, wherein:

Figure 1 is a diagrammatic view illustrating the electrical system for operating the engraving tools in accordance with the reflection of light from the record or pattern;

Figure 13 is a wiring diagram illustrating the control for the construction shown in Figure 12.

Although it will be understood as this description proceeds that my improved engraving apparatus may be advantageously employed to engrave numerous different articles, nevertheless, for the purpose of illustration, I have shown my engraving apparatus as especially designed to engrave glassware, such as tumblers and the like. It will also be apparent as this description proceeds, that the apparatus is entirely automatic in operation and is capable of accurately engraving any desired characters or designs in the surface of a plurality of articles of glassware simultaneously. As a consequence, my improved engraving apparatus offers the possibility of supplying engraved glassware to the trade at a cost only slightly above plain glass articles and at a cost commensurate with glassware having the characters or designs merely painted or printed thereon.

In general, a plurality of articles of glassware, such as the tumblers A, are supported in spaced relation to each other for both rotation and vertical movement relative to the engraving tools B. Upon reference to Figure 6, it will be noted that an engraving tool B is positioned opposite each of the tumblers A and the tools are mounted as a unit on a beam C supported for oscillation in directions to effect movement of the tools into and out of engagement with the adjacent surfaces of the tumblers A.

As shown in Figure 5 of the drawings, the beam C is moved in a direction to engage the tools B with the articles of glassware by means of an electromagnet D and is moved in the opposite direction by means of the spring E. In other words, when the electromagnet D is energized, the beam C is moved toward the front side of the machine to cause the tools to move into engagement with the articles of glassware and when the electromagnet is de-energized, the spring E moves the beam C in the opposite direction to cause the tools B to travel away from the articles of glassware.

The operation of the electromagnet D is controlled in accordance with the design or record it is desired to reproduce on the articles of glassware and, in the present instance, the record or design is carried by a revoluble drum F, shown in Figure 5, as supported centrally of the apparatus for vertical movement as a unit with the articles of glassware. The characters or design, applied to the drum F, are shaded and are scanned by means of an optical unit G supported opposite the drum F. The optical unit G comprises principally a projector H and a pair of photo-electric cells I. The projector H has a source of illumination in the form of an electric light bulb J adjustably supported at the rear end of the lens barrel K and is also provided with condenser lenses L for directing the light through the aperture M formed in a disk supported in the barrel K at the front side of the lenses L. The light passing through the aperture M is focused by the objective lenses N on the surface of the drum F upon which the record or pattern is supported. It will be understood that the light projected by the lenses N is in the form of a beam having an extremely small area on the surface of the record, and the light reflected from the surface of the record is intercepted by the photoelectric cells I supported on the optical unit G at opposite sides of the front end of the lens barrel K. It may be pointed out at this time that the reflected light is cast on the photoelectric cells I in a diffused state and this is desirable, since it insures a more uniform output of the photoelectric cells, irrespective of the variations in sensitivity of different portions of the light sensitive plates of the cells. This arrangement has been found to be much more satisfactory than in cases where the reflected light is focused on the light sensitive plates of the cells, since with the latter principle of operation, there is a possibility that as the focused beam of light contacts with different portions of the plates of the cells varying in sensitivity, a corresponding variation in the output of the cells would result and this variation would be reflected in the accuracy of the engraver.

The photoelectric cells I are rendered conductive when the beam of light from the projector intercepts the light portion of the record or design on the drum F and are rendered non-conductive when this beam of light intercepts a dark portion of the record. When the photoelectric cells are conducting, an electron flow is effected from the cathodes of the cells to the anodes of the latter in proportion to the intensity of the light reflected from the record, and the resulting flow of current through the photoelectric cells is amplified by the amplifier O. For the purpose of illustration, the amplifier circuit is shown as identical to the one illustrated and described in detail in the Charles R. Thorpe application, Serial No. 46,143, filed June 7, 1937. Briefly described, the amplifier circuit is such that the potential of the output circuit of the last stage Q which is connected to the load coil P of the electromagnet D, is reduced by the amplified photoelectric cell current to such an extent as to de-energize the electromagnet and permit the retracting spring E to move the beam C in a direction to withdraw the tools B from the articles of glassware. In other words, the last stage Q of the amplifier circuit is rendered non-conductive when the beam of projected light intercepts the light portion of the characters or pattern on the drum F and, as a consequence, no current flows through the load

coil of the electromagnet D. On the other hand, when the beam of projected light intercepts a dark portion of the design or characters on the drum F, the last stage Q of the amplifier is rendered conductive and, as a result, a high current flows through the plate circuit of the tubes in this last stage. Inasmuch as the load coil P is connected in the plate circuit of the tubes in the last stage Q of the amplifier, it follows that the electromagnet D will be energized and the tools B moved toward the work by the beam C.

The amplifier O is of the direct current amplification type having a plurality of amplifier tubes 11a, 12a, 13a, and 14a. The last stage preferably has two tubes 14a connected together in parallel so that the output is greater than that of any one of the tubes. Each of the tubes 11a, 12a, and 13a comprises a grid 15a, a plate 16a, and a cathode 17a with its heating element 18a, which is shown herein as being of the filament type. Each of the tubes 14a, on the other hand, comprises a grid 19a, a plate 20a, and a filament 21a which also acts as a cathode.

The output or plate circuit of each preceding tube is conductively coupled to the grid of the succeeding tube and the plate or output circuits of the two parallel tubes 14a are connected to the load coil P of the electromagnet D through a resistor 23a. Upon reference to Figure 1, it will be noted that a power pack 24a of conventional design provides low voltage alternating current for the filaments 18a of the tubes 11a, 12a, and 13a. It also provides a rectifier of the full wave type which supplies a high voltage direct current across the resistor 25a and the latter in turn supplies the proper current to the plate circuits of the tubes 11a, 12a, and 13a.

Similar elements of the tubes 14a are connected together to provide the multiple operation desired and a second rectifier 26a supplies the plate circuit of these tubes. The plate circuit of the tubes 14a comprises a resistor 27a, the load coil P, the resistor 23a, the two plates 20a, the filaments 21a, and a resistor 28a. Starting at the positive end of the resistor 27a, the current flows through the load coil P, resistance 23a, plates 20a, through the tubes 14a to the filaments 21a to the resistor 28a and back to the resistor 27a. Beginning at the center tap of the resistor 28a, the grid circuit of the tubes 14a includes the C battery, with polarity indicated, and resistor 30a conductively connecting the grids to the plate of the tube 13a.

Having described in general the several circuits of the amplifier, reference will be made to the operation of the system. Assuming, first, that the beam of light cast by the projector intercepts a dark portion of the record so that no light is reflected from the record into the photoelectric cells, it will be noted that no current is generated in the cells and that, accordingly, the plate current of the first tubes 11a is zero. In this connection, it will be noted that the grid circuit of tube 11a, starting from the cathode 17a, includes a variable resistor 31a, a resistance 32a, and also the portion of the high resistance 25a between the negative end of the latter and the cathode tap 33a. This portion of the resistor 25a is in parallel with the variable resistor or potentiometer 31a. Also, in parallel to the grid circuit of the tube 11a are the photoelectric cells and that portion of the high resistor 25a from the negative end of the latter to the photoelectric cell tap 34a on the resistor 25a.

Inasmuch as the cathode 17a of the tube 11a

is connected to the high resistor 25a by the tap 33a, it follows that the potential of the cathode depends on the location of the tap 33a with respect to the negative end of the resistor 25a, and by tracing the grid circuit of this tube 11a through the resistance 32a to the tap on the resistor 31a, it will be noted that the grid 15a is at a negative potential with respect to the cathode 17a by approximately the voltage at the cathode tap 33a. It will, of course, be understood that this voltage may be varied between zero and the amount at the cathode tap 33a by altering the location of the tap of resistor 32a. The output or plate circuit of the tube 11a, starting from the plate tap 36a on resistor 25a, includes resistor 37a, plate 16a, cathode 17a, tap 33a to resistor 25a and through the latter to the tap 36a. However, with the grid of the tube 11a biased in the manner outlined above, there is no current passing through the plate circuit and the meter in this circuit registers zero.

In view of the fact that there is no current flowing in the plate circuit of the tube 11a, there will be little or no drop in voltage across the resistor 37a and the voltage at the plate terminal of the tube 11a and the grid terminal of the tube 12a will be the voltage at the tap 36a on the resistor 25a. It will be observed from Figure 1 that the tap 36a for the grid of the tube 12a is at a higher potential than the tap 38a serving the cathode of the tube 12a and, as a consequence, the grid of the tube 12a is positive with respect to its cathode. The voltage of the grid is substantially the same as the voltage at the tap 36a because there is no current in the plate circuit of the tube 11a and, therefore, there is practically no voltage drop across the resistor 37a.

Owing to the fact that the grid of the tube 12a is positive with respect to the cathode of this tube, current will flow in the plate circuit of the tube 12a and a voltage drop will result across the resistor 39a. It also follows from the above that the voltage at the plate of the tube 12a and the grid of the tube 13a is lower than the voltage at the tap 40a on the resistor 25a by an amount depending upon the current flowing in the plate circuit of the tube 12a. In other words, although the grid tap 40a of the tube 13a is at a higher potential than the cathode tap 41a, the voltage on the grid of tube 13a is lower than the voltage at the tap 40a by an amount equal to the drop through the resistance 39a caused by the current flowing through the plate or output circuit of the tube 12a. With the grid of the tube 13a biased in this manner, no current will flow through the plate or output circuit of this tube which, starting from the tap 45a on the resistor 25a, includes the choke coil 46a, resistor 30a, choke coil 48a, plate 16a, cathode 17a and that portion of the resistor from the tap 41a to the tap 45a. Inasmuch as there is no current passing through the output circuit of the tube 13a, there will be little or no voltage drop across the resistor 30a.

The resistor 30a is located in the grid circuit of the tubes 14a and, since there is practically no current flowing through this resistor, it follows that the voltage at the grids 19a is the C battery voltage supplied by the battery 50a connected in the grid circuit with the polarity noted in Figure 1. With the grid of the tubes 14a biased in the above manner and with the output voltage of the rectifier 26a dropped across the plate circuit of the tubes 14a, a high current will flow through the plate circuit of these tubes which includes the load coil P of the electromagnet. As a conse-

quence, the electromagnet is energized when no light is reflected from the surface of the pattern on the photoelectric cells.

Assuming now that light is reflected from the surface of the pattern onto the light sensitive cells, it will be noted that this light acts on the cells to reduce the resistance of the latter to such an extent as to cause an electron flow between the anodes and cathodes of the cells. As a result, current flows through the cells from the anodes to the cathodes and this current causes a voltage drop across the resistor 32a. This voltage drop is positive with respect to the cathode of the first tube 11a and has a counteractive effect on the fixed grid bias of this tube tending to make the grid less negative. When this condition exists, current flows through the plate circuit of the first tube and the passage of this current through the resistor 37a causes a voltage drop across this resistor making the grid of the second tube 12a less positive, with the result that the plate current of tube 12a is appreciably reduced. The cessation of current flow in the plate circuit of the tube 12a causes the voltage on the grid of the tube 13a to increase to the voltage at the tap 40a. In other words, the grid of the tube 13a becomes more positive and causes current to flow through the plate circuit of the tube 13a. As current flows through the plate circuit of the tube 13a, the voltage drops across the resistor 30a and the voltage at point 51a is lower than the voltage at point 52a. This makes the grids of the tubes 14a more negative by an amount equal to the voltage drop across resistor 30a and, as a result, the flow of current through the plate circuit of the tubes 14a is discontinued. Inasmuch as the load coil P of the electromagnet is located in the plate circuit of the tubes 14a, it follows that the magnet will be de-energized and the spring E will move the tool in a direction away from the work and the optical unit in a direction toward the pattern.

Although the present engraving apparatus may be designed to simultaneously engrave any number of articles of glassware, nevertheless, for the purpose of illustration, I have shown the machine as equipped to engrave twelve articles at the same time from a single optical unit and pattern. Upon reference to Figure 2, it will be noted that the glass articles A, to be engraved, are supported in a line with sufficient space therebetween to provide the required clearance, and are arranged in two groups, designated in Figure 2 by the reference characters 20 and 21. Each group contains six articles of glassware and the drum F is positioned between the articles of glassware at the adjacent ends of the two groups. Referring now to Figure 4, it will be noted that the articles of glassware, to be engraved, and the drum F, carrying the design or characters to be reproduced, are mounted upon a carriage 22 which, in turn, is mounted for vertical sliding movement on the column 23. In the present instance, the carriage 22 is fed at a relatively slow speed in an upward direction by means of a revolute vertically extending screw 24 having the lower end threaded in a nut 25 mounted on the carriage 22 and having the upper end operatively connected to a drive shaft 26 through the medium of reduction gearing 27. As shown in Figure 5, the reduction gearing comprises a gear 28 secured to the upper end of the screw 24 and meshes with a pinion 29 journaled on a stub shaft 29'. The pinion 29 is driven by a gear 30 having teeth on the periphery thereof meshing with suitable

splines on the shaft 31 which extends upwardly from the screw 24 in alignment therewith, and is rotatably supported in a vertical sleeve 32 forming a part of the bracket 33. The shaft 31 is rotated by means of a worm 34 secured to the drive shaft 26 and meshing with a worm wheel 35 secured to the shaft 31. 5

From the above, it will be noted that rotation of the drive shaft 26 not only effects a rotation of the vertical shaft 31, but also causes the screw 24 10 to rotate relative to the nut 25 in a direction to feed the carriage 22 upwardly. Upon reference to Figure 8, it will be noted that the drive shaft 26 extends for substantially the full length of the machine and has a gear 36 secured to one end 15 thereof. The gear 36 meshes with a pinion 37 secured to a stub shaft 38 which, in turn, is operatively connected to a three-phase electric motor 39 through the medium of a flexible shaft 40 and worm gearing 41. 20

When the carriage 22 assumes the uppermost position thereof shown in Figure 5, the circuit to the electric motor 39 is discontinued and the signal light 42 is illuminated to indicate to the operator that the carriage 22 has been fed to the 25 limit of its upward travel. The above is accomplished, in the present instance, by locating an adjustable stop 43 on the carriage in such a position that when the latter approaches its uppermost position, the stop engages the toggle switch 30 control lever 44 and actuates the latter to open the circuit to the motor 39. When the operator receives the signal from the lamp 42 that the carriage has approached the end of its vertical feed, he depresses the foot operated control 45 and in 35 so doing releases the nut 25 from the screw 24. This permits the carriage 22 to lower by the action of gravity until the surface 46 at the bottom of the carriage 22 engages the adjustable stop 47 mounted on the column 23. The rate of downward movement of the carriage 22 relative to the nut 25 is controlled by a fluid actuated dash pot 48 having a cylinder mounted on the column and having a piston 49 connected to the carriage by means of the rod 50. As the carriage approaches 45 its lowermost position, the toggle switch control arm 44 is again operated to close the circuit to the motor and thereby continue rotation of the screw 24 by the drive shaft 26. It will, of course, be understood that when the carriage assumes 50 its lowermost position, the operator releases the foot operated control pedal 45 to permit the nut 25 to assume its operative position with respect to the screw 24 so that when the circuit to the prime mover 39 is again closed, the carriage will 55 be fed in an upward direction. The toggle switch arm 44 is actuated to close the circuit to the motor by means of a second adjustable stop 51 located on the carriage in a position to engage the arm 44 and actuate the switch in timed relation 60 to downward movement of the carriage 22.

It has previously been stated that the nut 25 is rendered operative and inoperative by manipulation of the foot pedal 45. In this connection, it will be noted that the nut 25 comprises complementary pivotally connected sections 53 and 54 normally held in their closed positions in gripping relation to the screw 24 by means of a spring 55. The sections are pivotally connected together by means of a vertically extending pintle 70 56 and each section is provided with a laterally outwardly extending projection 57 adapted to be engaged by suitable dogs 58 located upon opposite sides of the nut sections. The dogs 58 are shown 75 in Figure 5 as being secured to a rockshaft 59 75

rotatably supported on the column 23, with the axis thereof extending at right angles to the pintle 56. The rockshaft 59 is operatively connected to the foot operated control 45 in such a manner that when the latter is depressed, the dogs 58 cooperate with the projections 57 on the hinged parts to swing the latter outwardly against the action of the spring 55 and thereby release the nut 25 from the screw 24. As shown in Figure 5, an arm 60 is secured to the rockshaft and the free end of this arm is pivotally connected to the free end of a vertically extending rod 61 having the lower end pivotally connected to the foot pedal 45, adjacent its pivotal connection 62, with the lower end of the column 23 of the machine. With the above construction, it will be understood that when the pedal 45 is depressed, the nut 25 is released from the screw 24 permitting the latter to move downwardly with the carriage 22 and the spring 55 will return the cooperating sections of the nut into engagement with the screw 24 when the pedal 45 is released.

In view of the fact that each of the several articles of glassware to be engraved is mounted on the carriage 22 and inasmuch as the drum F, carrying the characters or record to be engraved on the glassware, is also mounted on this carriage, it follows that these elements will be moved vertically as a unit. Also, in the present instance, the tools B for engraving the various articles of glassware and the optical unit G associated with the drum F are supported independently of the carriage 22 so that as different portions of the surface of the drum F, throughout the length thereof, register with the optical unit G, corresponding portions of the articles of glassware are brought into registration with the tools B. The extent of vertical travel of the carriage 22 is predetermined in accordance with the maximum extent of the record or design on the surface of the drum in the direction of length of the latter so that the entire width of the design may be scanned and reproduced on the articles of glassware.

It has also been stated above that the drum F and articles of glassware are rotated during vertical travel thereof so that the entire length, as well as the width of the record or design on the drum F is scanned and reproduced on the articles of glassware. Upon reference to Figure 5, it will be noted that the drum F is seated upon the upper end of the sleeve 32 and is secured to the shaft 31 for rotation therewith as a unit. Each of the articles of glassware A is supported upon a revolute disc 63 of flexible material and the latter, in turn, is secured to a hub 64 having a barrel portion secured to a vertical shaft 65. The shaft 65 is revolvably mounted in a sleeve 66 forming a vertical extension of a bracket 67 and the lower end of the shaft 65 has a worm wheel 68 secured thereto in a position to mesh with a worm 69 secured to the drive shaft 26. The arrangement is such that when the drive shaft 26 is revolved by the prime mover 39, each of the articles of glassware and the drum F are rotated relative to the tools B and optical unit G, respectively.

The articles of glassware are centered upon the discs 63 by means which is automatically adjustable to effectively engage the inner surfaces of the glass tumblers, irrespective of the degree of taper or contour of these surfaces. In detail, the centering means includes a sleeve 70 slidably mounted on the upper end of the shaft 65 and having radially outwardly extending circumferentially spaced flexible pads 71 adapted to engage

the inner surface of the glass tumbler adjacent the open end of the latter. The sleeve 70 is normally urged in an upward direction to insure firm engagement of the pads with the inner tapered surface of the tumbler by means of a spring 72 surrounding the shaft 65 between the lower end of the sleeve and the disc 63. As shown in Figure 7, the upper end of the spring 72 engages the bottom of the sleeve 70 and the lower end of the spring abuts the disc 73. In addition, the centering means comprises a second sleeve 74 slidably mounted on the upper end of the sleeve 70 and having radially outwardly extending circumferentially spaced flexible pads 75 adapted to frictionally engage the inner tapered surface of the glass tumbler at points spaced vertically above the pads 71. The pads 75 are normally urged into frictional engagement with the inner surface of the glass tumbler adjacent the bottom of the latter by means of a coil spring 76 surrounding the sleeve 74. The lower end of the coil spring 76 abuts the radially outwardly extending portions of the sleeve 70 and the upper end of the coil spring engages an annular shoulder 77 on the sleeve 74. With this construction, it will be apparent that the glass tumblers are effectively centered on the discs 63, irrespective of the degree of taper of the inner surfaces of the tumblers.

The tumblers are maintained in clamping engagement with the discs 63 by means of suction and, for accomplishing this result, communication is established between the interior of each tumbler A and a suction line 78. As shown in Figure 7, each of the shafts 65 is axially bored to provide a passage 80 having the upper end communicating with the interior of the tumbler through a radially extending passage 81 and having the lower end communicating with the interior of the suction line 78 through the medium of a flexible conduit 82. In Figure 3, the suction line is shown as extending for the full length of the machine and the open end of the suction line communicates with a suitable pump (not shown) through the medium of a three-way valve 83. The valve 83 is manually controlled and, when in one position of adjustment, opens communication between the pump (not shown) and the suction line 78. When the valve is turned to another position, communication is established between the atmosphere and suction line in order to permit the tumblers to be readily removed from the discs 63.

It has previously been stated that the shaft 31 for rotating the drum F and the shafts 65 for rotating the glass tumblers A are supported on brackets. The brackets 67 for rotatably supporting the article carrying shafts 65 are each provided with lateral extensions 85 pivotally mounted on the drive shaft 26 in a manner to permit the several articles of glassware A to be swung in a direction away from the tools B prior to downward movement of the carriage 22 to its initial starting position. For the purpose of swinging the brackets to their inoperative positions, I provide a shaft 86 extending parallel to the drive shaft 26 and supported in the machine frame for rocking movement. Secured to the rockshaft 86 opposite one of the lateral extensions 85 of the brackets is a cam 88 having an abrupt shoulder 89 effective upon rocking movement of the shaft in one direction to engage an adjustable stop 90 carried by an extension 91 on the portion 85 of each bracket 67. As rocking movement of the shaft 86 in the above direction continues, the

shoulders 89 on the cams 88 cooperate with the adjustment stops 90 on the brackets 67 to swing the latter about the axis of the drive shaft 26 in a direction away from the tools B and the optical unit G.

In the present instance, the shaft 86 is rocked manually to move the brackets 67 away from the tools by means of an arm 92 secured to one end of the shaft 86 and having a latch element 93 cooperating with a latch plate 94 on the carriage to hold the shaft 86 in a position wherein the tumblers on the brackets 67 are in their inoperative positions relative to the tools. In Figure 9 of the drawings, the latch element is shown as having a pawl 96 normally urged into frictional engagement with the latch plate 94 by means of a spring 97 and adapted to engage in a notch 98 in the periphery of the plate 94. The notch 98 is so located in the plate 94 that when the pawl is in engagement therewith, the tumblers on the brackets 67 are in their inoperative positions with respect to the tools.

In actual practice, the brackets 67 are swung to their inoperative positions when the carriage 22 has been advanced to its extreme uppermost position and before the foot pedal 45 is manipulated to permit lowering of the carriage to its initial starting position. After the brackets aforesaid have been tilted or swung to their inoperative positions and before the carriage 22 is lowered by manipulation of the pedal 45, the three-way valve 83 is manipulated to relieve the vacuum within the engraved glass tumblers A. These tumblers are then removed and replaced with an additional set of tumblers to be engraved and, if it is desired to engrave a different pattern on these tumblers, the design or characters on the drum F are replaced. Upon completion of the foregoing operations, the three-way valve 83 is again operated to establish a vacuum in the glass tumblers A and to thereby clamp the tumblers to the supporting discs 63. After this is accomplished, the pedal 45 is operated to lower the carriage 22 and the arm 92 is manipulated to swing the brackets 67 back to their operative positions. As stated above, as soon as the carriage 22 assumes its lowermost position, the vertical feed is automatically started and the tumblers are engraved in accordance with the pattern on the drum F.

The bracket 33 supporting the drum shaft 31 is also provided with a lateral extension 33' pivotally mounted on the drive shaft 26 for swinging movement toward and away from the optical unit. Proper positioning of the pattern carrying drum F relative to the optical unit is secured by a pair of adjustable set screws 99 shown in Figure 5 as being so positioned as to hold the drum F from swinging movement about the shaft 26 after the desired adjustment is obtained.

In the previous description, reference was made to the fact that the tools B are moved into and out of engagement with the surface of the tumblers A by means of the oscillating beam C. As shown in Figures 6 and 7, a high speed electric motor 100 is supported between adjacent tumblers A at the rear side of the latter and are carried by brackets 101 which, in turn, are secured to the front edge of the longitudinally extending beam C. In Figure 6, the high speed electric motor 100 is shown as having a drive shaft 102 extending axially therethrough and being of sufficient length to support the tools B in registration with the rear sides of the tumblers. In accordance with this invention, the tools B are in the form of 75 abrasive discs and each tool is rotatable in a

plane including the vertical axis of the registering tumbler A.

In the brief description of the invention noted above, reference has been made to the fact that the beam C, having the tools B thereon, is oscillated toward and from the tumblers by means of the electromagnet D which is controlled by the optical unit G in accordance with the shading of the design on the drum F. In detail, the electromagnet is shown in Figure 5 as having a magnetic field 105 and load coil 106 secured to a plunger 107, which in turn is mounted in the core 108 of the electro-magnet for sliding movement into and out of the field 105. Movement of the load coil 106 into the field 105 is resisted by the spring E and effects a movement of the tool carrying beam C toward the glass tumblers A by virtue of the operative connection 109 between the plunger 107 and the forward edge of the beam C. As shown in Figure 5, the operative connection includes a lever 110 having the lower end connected to the plunger 107 and having the upper end fulcrumed on a tapered adjustable pin 111. In addition, the connection 109 comprises a second lever 112 having the lower end pivotally interconnected with the lever 110 between the fulcrum 111 and the plunger 107 by means of a link 113. The upper end of the second lever 112 is provided with a hooked portion 114 having a V-shaped projection 115 fulcrumed in a correspondingly shaped groove 116 formed in a member 117 which is fixed to the machine frame. A stud 118 is secured to the lever 112 intermediate the ends of the latter and is provided at its forward end with a conical portion 119 adapted to contact an adjustable insert 120 secured to the beam C at the rear edge of the latter intermediate the ends of the same. The adjustable insert 120 at the rear edge of the beam C is maintained into engagement with the forward end of the stud 118 by means of the springs 121 having the forward ends secured to the beam C and having the rear ends secured to the machine frame through the medium of the adjustable studs 122.

With the above construction, it will be noted that when the load coil 106 is energized, the plunger 107, together with the coil, is moved forwardly of the machine into the field 105. The lower end of the lever 110 is correspondingly moved in the same direction about its fulcrum 111 and the lever 112 is moved by the lever 110 in a forward direction about its fulcrum 116. As a result, the beam C is moved in a forward direction and, since the tools B are carried by the beam, it follows that these tools will be moved into engagement with the glass tumblers. On the other hand, when the load coil 106 is de-energized, the spring E moves the plunger 107 in a rearward direction and through the connection 109 effects a movement of the tools B in a direction away from the glass tumblers A. With the circuit diagram, shown in Figure 1, current flows through the plate circuit of the last stage Q of the amplifier to energize the load coil 106 of the electromagnet D when the photoelectric cells are non-conducting and, when light is reflected on the photoelectric cells, the flow of current through the plate circuit of the last stage Q is discontinued with the result that the load coil 106 is de-energized and the plunger 107 is moved in the opposite direction by the spring E. In accordance with the foregoing, the tools operate on the glass tumblers when the photoelectric cells are non-conducting and are moved out of 75

engagement with the tumblers when the cells are conducting.

Having described the manner in which the beam is oscillated to actuate the tools, reference is now made to the particular means selected herein for supporting the beam. Upon reference to Figure 5, 6, and 7, it will be noted that the beam is supported adjacent its longitudinal edges on the bars 125 having the opposite edges V-shaped and respectively engaging correspondingly shaped grooves 126 in the bottom surface of the beam and adjacent portions of the machine frame. The construction is such as to reduce friction to oscillation of the beam to the minimum and at the same time provide a stable support for the beam. As shown in Figures 2, 7, and 8, the stability of the beam C is appreciably increased by means of weights 127 extending for substantially the full length of the beam and suspended from the latter through the medium of the chains 128. The weights impart the required stability to the beam without increasing the inertia of the latter and, as a consequence, very little power is required to oscillate the beam.

Referring again to Figure 7 of the drawings, it will be noted that the glass tumblers A are normally urged in a direction toward the tools B by means of the springs 129 acting upon the brackets 67 and adjustably supported on the machine frame, as at 129', to provide for varying the tension of the spring. The movement of the glass tumblers A toward the tools B by the springs 129 is limited by means of the positioning members or feelers 130 having a tapered forward end portion 131 engageable with the rear side of the glass tumblers immediately adjacent the tools B. The location of the feelers 130 is such that these feelers oppose the action of the springs 129 and definitely limit the extent of movement of the tumblers A toward the tools B. In other words, one function of the feelers is to vary the depth of cut of the tools and, for accomplishing this result, the feelers are adjustably mounted in brackets 132 having portions secured to a plate 133 which, in turn, is supported on the top of the column 23 in the manner clearly shown in Figures 2 to 8, inclusive. Each of the feelers is adjusted by means of a control wheel 134 having notches 135 in the periphery thereof adapted to cooperate with a spring pressed detent 136 on the bracket 132 to not only prevent accidental movement of the feelers relative to the tools, but to also indicate predetermined increments of adjustment of the tools.

In accordance with the present invention, the feelers also function to secure a uniform predetermined depth of cut, irrespective of the wear of the tools and irrespective of variations in the glass tumblers A. For accomplishing this result, the plate 133 is mounted for sliding movement toward and away from the glass tumblers A. The plate 133 is yieldably urged in a forward direction toward the glass tumblers A by means of the springs 137, shown in Figures 6 and 8 as having the forward ends abutting the rear edge of the plate 133 and as having the rear ends engaging a fixed abutment 138 extending upwardly from the machine frame. Upon reference to Figures 5 and 6, it will be noted that the springs 137 are assisted in moving the plate 133 toward the glass tumblers by means of a spring 139 located intermediate the ends of the plate. As shown in these figures, the rear end 75 of the spring is secured to the plate 133 and the

forward end of the spring 139 is secured to a stud 140 which extends through an elongated opening 141 in the plate and is threaded into the machine frame. The springs for urging the plate 133 in a direction toward the glass tumblers counteract the springs 129 for urging the glass tumblers toward the tools and, in the present instance, the former springs are slightly stronger so that there will be no danger of the glass tumblers A moving toward the tools against the action of the springs 137 and 139. Of course, provision is made herein to prevent the stronger springs 137 and 139 from moving the glass tumblers A against the action of the weaker springs 129 in a direction away from the tools. This is accomplished by a pair of templets 145 secured to the carriage 22 adjacent opposite ends of the feeler plate and engaged by rollers 168 carried by the feeler plate. The rollers are normally urged into engagement with the templets 145 by the springs 137 and 139 acting on the feeler plate 133. The tapered ends of the feelers extend beyond the templets into engagement with the tumblers A a distance depending upon the adjustment aforesaid of the feelers, or upon 25 the depth of cut of the tools.

Inasmuch as the templets 145 determine the extent of movement of the feelers toward the tumblers A, it follows that the surfaces of the templets engaged by the feeler brackets must have a shape predetermined in accordance with the contour of the glass tumblers being engraved so that the relationship between the tool and feeler will change in dependence upon the contour of the tumblers to secure a uniform 35 depth of cut. In this connection, attention is called to Figure 11 of the drawings, wherein it will be noted that the degree of curvature of the surface of the tumbler to be engraved changes substantially in the direction of length of the 40 tumbler and, in cases of this character, the rear surfaces of the templets 145' are shaped in the manner illustrated to maintain the relationship between the feeler and tool required to secure a uniform cut throughout vertical movement of 45 the tumbler.

Referring now more in detail to Figure 11, it will be noted that in order to illustrate the manner in which the present machine maintains a uniform cut, irrespective of the contour of the 50 surface of the article being engraved, I have selected a glass goblet A' having a mouth portion 165 of reduced diameter and having a base portion 166 of less diameter. The relative diameters of the above portions of the goblet are such that a substantial curvature exists in the side walls of the goblet and, in cases of this character, it is necessary to change the position of the feeler relative to the tool in order to insure a uniform 55 cut during the engraving operation. The necessary change in location of the feeler 130 with respect to the tool B is obtained by predeterminedly shaping the face 167 of the templet engaged by the roller 168 on the feeler plate 133.

The goblet A' is shown in its lowermost position by the full lines in Figure 11 and the surface 167 on the templet 145' is such that the feeler 130 assumes the full line position thereof relative to the tool when the goblet is in its lowermost position. As the goblet A' and the templet 70 145' are moved upwardly relative to the tool B and feeler 130 to its dotted line position illustrated in Figure 11, the goblet is swung in a direction away from the tool B by the feeler 130 and the latter is moved toward the goblet under 75

the action of the springs 137 by the surface 161 of the templet until the feeler assumes the dotted line position thereof relative to the tool B. As a result, the surface of the goblet to be engraved 5 is adjusted relative to the tool by the feeler so that a uniform cut is effected, irrespective of the contour of the side walls of the goblet.

In order to enhance the cutting operation, provision is made herein for supplying a stream 10 of cooling medium, such as water, to the surface of the tumblers being engraved. For accomplishing this result, I provide a water manifold 147 extending substantially the full length of the machine and communicating at longitudinally spaced points with suitable conduits 148 having 15 the discharge ends positioned to direct the stream of water against the tumblers adjacent the tools B. In Figure 7 of the drawings, I have shown suitable deflectors 150 on the feeler brackets 132 and these deflectors form a support for the free 20 ends of the conduits 148. Inasmuch as the feeler brackets 132 move with the feeler plate 133, the manifold 147 is supported on the feeler plate by means of the clamps 152.

Referring again to Figure 5 of the drawings, 25 it will be noted that the optical unit G is mounted on a plate 154 which, in turn, is supported on the machine frame for sliding movement toward and away from the drum F. The plate 154 is guided at opposite edges thereof by means of the rollers 155 and is normally urged 30 in a direction toward the drum F by means of a relatively light spring 156 having one end secured to the upper end of the stud 140 and having the opposite end secured to the optical unit G. In this connection, it may be pointed out 35 that the plate 154 is slotted, as at 157, to receive the stud 140 and spring 139 associated with the feeler plate 133. The optical unit is maintained 40 in proper spaced relationship to the design on the drum F by means of a roller 160 supported on the optical unit and frictionally engaging the drum F. It will be apparent from the foregoing 45 that the roller 160 is maintained into frictional engagement with the surface of the drum, irrespective of any irregularities in the latter and this is highly advantageous in that it offers the possibility of maintaining the focal distance between the lenses N and pattern on the drum 50 uniform throughout the scanning operation. As a consequence, the depth of cut of the tools B is not effected by irregularities in the surface of the drum F and extremely accurate results may be secured.

In cases where it is desired to engrave only a 55 portion of the surface of the article, it is advantageous from the standpoint of increased production to appreciably increase the speed of rotation of the articles being engraved. For the 60 purpose of illustration, it will be assumed that a pattern is engraved on one side only of the glass article and that the latter is rotated at a relatively slower rate of speed during the engraving operation. In general, when the optical unit is 65 scanning the pattern on the drum F, or when the engraving tool B is cutting the surface of the article to be engraved, the three-phase motor 39 is connected to a relatively low cycle current supply in order to rotate the articles at a relatively slow speed. On the other hand, when the 70 engraving tools B are moved away from the article or, in other words, when the pattern on the drum F has been advanced beyond the optical unit, the three-phase motor 39 is automatically connected to a relatively high cycle current sup-

ply so that the articles are revolved at a higher rate of speed.

For accomplishing the above result, I provide a templet in the form of a drum 170 secured to the pattern carrying drum shaft 31 for rotation therewith as a unit and having an area of the side wall thereof relieved, as at 171. The area of the relieved portion corresponds substantially to the area of the pattern to be engraved on the articles of glassware and the surface of the 10 templet drum having the relieved portion therein is adapted to be engaged by a follower 172. The templet drum is secured to the shaft 31 with the relieved portion so positioned with respect to the pattern on the drum F that when the latter is being scanned by the optical unit, the follower 172 is engaged with the relieved area of the templet drum 170. Upon reference to Figure 13, the follower is connected to a toggle switch 173 arranged in a control circuit 174 and 15 adapted to be automatically opened by a spring 175 when the follower engages in the relieved area 171 of the templet drum 170. The circuit 174 includes a relay 176 which is normally maintained by the spring 177 in a position wherein 20 a relatively low cycle circuit 178 is closed to the electric motor 39.

As a result of the foregoing, it will be noted that when the follower 172 is in the relieved area 171 of the surface of the templet drum 170, the 30 circuit 174 is opened by the switch 173 and the coil of the relay is de-energized permitting the spring 177 to close the relatively low cycle circuit to the motor 39. This circuit remains closed until the templet drum 170 is rotated sufficiently to 35 raise the follower 172 out of the relieved portion 171 and the switch 173 is closed by the resulting lateral movement of the follower. Closing of the circuit 174 by the switch 173 energizes the relay 176 to break the low cycle circuit 178 and close the 40 high cycle circuit 179. As a result of the above, the speed of the motor 39 is increased and since the latter is operatively connected to both the articles and drums F and 170, it follows that the speed of the latter will also be increased until the 45 follower again registers with the relieved area 171 of the surface of the drum 170. At this time, the switch 173 is again opened and the above cycle of operation is repeated.

In order to compensate for the acceleration 50 and deceleration of the articles to be engraved, the area of the relieved surface of the drum 170 is greater than the area of the pattern on the drum F to be engraved on the articles. The construction is such that the speed of rotation of the 55 articles to be engraved is reduced to the desired rate prior to the actual engraving operation.

It follows from the foregoing that I have provided an engraving machine rendering it possible to engrave a plurality of articles simultaneously 60 with the minimum attention on the part of the operator. It will also be observed that provision is made in the engraving machine for obtaining extremely accurate results, irrespective of the contour of the surface of the article to be engraved and notwithstanding any manufacturing inaccuracies that may exist in the articles or drum containing the pattern to be duplicated. It may be again pointed out that while the machine has been described in detail as adapted for engraving 65 glass tumblers, nevertheless, it is not limited to this specific use, since the construction thereof is such as to permit the same to be readily employed for engraving many other types of articles. Also, attention is called to the fact that 70 75

while a specific amplifying circuit has been shown for the purpose of illustrating the manner in which the tools are operated from the photoelectric cells, nevertheless, it is to be noted that various other circuits may be employed and, therefore, reservation is made to make such changes in the construction as may come within the purview of the accompanying claims.

What I claim as my invention is:

- 10 1. In apparatus for cutting a design in the surfaces of articles, means for supporting adjacent articles in spaced relation to each other, a pattern carrying the record to be duplicated on the surfaces of the articles, a revoluble drive shaft having tools adjacent the ends thereof and positioned with the tools opposite the surfaces of adjacent articles, means supporting said shaft for movement transversely of the axis thereof toward and away from the articles, means for rotating the shaft, an optical unit for scanning the record on the pattern including a light sensitive cell controlled by the record, and means controlled by the light sensitive cell for actuating the shaft supporting means to move said shaft and tools toward and away from the articles.
- 15 2. In engraving apparatus for cutting a design in the surfaces of articles, means for supporting adjacent articles in spaced relation to each other and for rotation about substantially parallel axes, a pattern carrying a predeterminedly shaded design, a prime mover having a drive shaft extending transversely to the axes of rotation of adjacent articles and having tools thereon registering with the surfaces of the articles upon which the design
- 20 35 on the pattern is to be reproduced, means supporting the prime mover for movement toward and away from the surfaces of adjacent articles, an optical unit for scanning the design on the pattern including a light sensitive cell controlled by said design, means controlled by the light sensitive cell for actuating the shaft supporting means to move said shaft and tools toward and away from the articles, and means for relatively moving the shaft and articles in accordance with the wear of the tools and in accordance with any variations in the surfaces of the articles to maintain a uniform depth of cut.
- 25 40 3. In apparatus for cutting a design in the surface of an article, a pattern carrying the design to be reproduced on the surface of the article, a tool supported opposite the surface of the article for movement toward and away from said surface, an optical unit for scanning the design on the pattern including a light sensitive cell controlled by the design, means controlled by the light sensitive cell for moving the tool toward and away from the article, and means movable independently of the tool in accordance with variations in the profile contour of the surface of the article for varying the position of the article relative to the tool to maintain substantially the same relationship between the surface of the article and tool irrespective of any irregularities in the surface of the article.
- 30 45 4. In apparatus for cutting a design in the surface of an article, a pattern carrying the design to be reproduced on the surface of the article, a tool supported opposite the surface of the article for movement toward and away from said surface, an optical unit for scanning the design on the pattern including a light sensitive cell controlled by the design, means controlled by the light sensitive cell for moving the tool toward and away from the article, and means operable independently of the light sensitive cell for adjusting the position of the article relative to the tool in accordance with variations in the

profile of the surface of the article to secure a uniform depth of cut.

5 5. In apparatus for cutting a design in the surface of an article, a pattern carrying the design to be reproduced on the surface of the article, a tool supported opposite the surface of the article, a prime mover having a rotatable drive shaft upon which the tool is mounted, means supporting the prime mover for movement toward and away from the article, an optical unit for scanning the design on the pattern including a light sensitive cell controlled by the design, means controlled by the light sensitive cell for moving the prime mover and tool as a unit toward and away from the work, and means movable independently of the prime mover for relatively adjusting the tool and article in accordance with variations in the profile contour of the surface of the article to secure a uniform dept¹ of cut.

10 20 6. In apparatus for cutting a design in the surfaces of articles, means for supporting adjacent articles in spaced relation to each other and for rotation about substantially parallel axes, a pattern carrying a design to be duplicated on the surfaces of the articles, a revoluble drive shaft extending transversely to the axes of rotation of the articles and having tools thereon registering with the surfaces of the articles, means supporting said shaft for movement transversely of its axis in directions toward and away from the articles, means for rotating said shaft, an optical unit for scanning the design on the pattern including a light sensitive cell controlled by said design, means controlled by the light sensitive cell for actuating the shaft supporting means to move said shaft and tools toward and away from the articles, and means for relatively moving the shaft and articles in accordance with the wear of the tools and in accordance with any variations in the surfaces of the articles to maintain a uniform depth of cut.

25 30 35 40 7. In apparatus for cutting a design in the surfaces of a plurality of articles, means for supporting the articles in spaced relation to each other, a pattern carrying the design to be duplicated on the surfaces of the articles, a tool supported opposite each article for movement toward and away from the surface of each article, a member supported for movement toward and away from the articles and forming a common support for the tools, an optical unit for scanning the design on the pattern including a light sensitive cell controlled by the design, and means controlled by the light sensitive cell for actuating said member to move the tools into and out of engagement with the surfaces of the articles upon which the design is to be reproduced.

45 50 55 60 8. In apparatus for cutting a design in the surfaces of a plurality of articles, means for supporting the articles in spaced relation to each other, a pattern carrying the design to be duplicated on the surfaces of the articles, a tool supported opposite each article for movement toward and away from the surface of each article, a beam fulcrumed adjacent opposite edges thereof for oscillation toward and away from the articles, means supporting each of the tools on said beam, an optical unit for scanning the design on the pattern including a light sensitive cell controlled by the design, and means controlled by the light sensitive cell for oscillating the beam to move the tools into and out of engagement with the surfaces of the articles upon which the design is to be duplicated.

9. In apparatus for cutting a design in the surface of an article, a pattern carrying the design to be duplicated on the surface of the article, a tool positioned opposite the surface of the article upon which the design is to be reproduced, a beam fulcrumed for oscillation toward and away from the articles, means supporting the tool on said beam, an optical unit for scanning the design on the pattern including a light sensitive cell controlled by the design, and means controlled by the light sensitive cell for oscillating the beam to move the tool into and out of engagement with the article.
10. In apparatus for cutting a design in the surface of an article, a pattern carrying the design to be duplicated on the surface of the article, a tool positioned opposite the surface of the article upon which the design is to be reproduced, a beam fulcrumed for oscillation toward and away from the articles, means supporting the tool on said beam, an optical unit for scanning the design on the pattern including a light sensitive cell controlled by the design, means controlled by the light sensitive cell for oscillating the beam to move the tool into and out of engagement with the article, and means stabilizing the action of the beam without increasing the inertia of the latter.
11. In apparatus for cutting a design in the surface of an article, a pattern for carrying the design to be duplicated on the surface of the article, a revolute tool, a rotatable support for the article mounted for swinging movement in a direction toward and away from the tool, yieldable means normally urging the support in a direction to engage the article with the tool, means limiting the extent of swinging movement of the article toward the tool and providing for securing a predetermined depth of cut, a support for the tool movable toward and away from said article, an optical unit for scanning the design on the pattern including a light sensitive cell controlled by the design, and means controlled by the light sensitive cell for moving the tool support toward and away from the article.
12. In apparatus for cutting a design in the surface of an article, a pattern for carrying the design to be duplicated on the surface of the article, a revolute support for the article mounted for swinging movement in opposite directions, yieldable means normally urging said support in one direction, a spring pressed member engageable with the article and opposing the action of the yieldable means aforesaid to limit swinging movement of the article in the above mentioned direction, a tool movable into and out of engagement with the surface of the article adjacent the point of engagement of the member aforesaid with the article, an optical unit for scanning the design on the pattern including a light sensitive cell controlled by the design, and means controlled by the light sensitive cell for moving the tool relative to the member into and out of engagement with the article.
13. In apparatus for cutting a design in the surface of an article, a pattern for carrying the design to be duplicated on the surface of the article, a revolute support for the article mounted for swinging movement in opposite directions, yieldable means for swinging the support in one direction, a member engageable with the article to limit the extent of swinging movement of the article in the last named direction by the yieldable means, a revolute tool supported opposite the article adjacent the point of engagement of

said member with the article, means supporting the tool for movement toward and away from the article, an optical unit for scanning the design on the pattern including a light sensitive cell controlled by the design, means controlled by the light sensitive cell for moving the tool toward and away from the article, and means for adjusting said member to vary the depth of cut of the tool.

14. In apparatus for cutting a design in the surface of an article, a pattern for carrying the design to be duplicated on the surface of the article, a revolute support for the article mounted for swinging movement in opposite directions, means for feeding the support in one direction, yieldable means normally tending to swing the support in one direction, a spring pressed member engageable with the article and opposing the yieldable means to limit swinging movement of the support in the last named direction, a revolute tool supported adjacent said member for movement into and out of engagement with the article, means effective upon feeding the support in the direction aforesaid relative to the tool and member to guide the latter in accordance with the profile contour of the article to maintain a uniform depth of cut, an optical unit for scanning the design on the pattern including a light sensitive cell controlled by the design, and means controlled by the light sensitive cell for moving the tool into and out of engagement with the article.

15. In apparatus for cutting a design in the surface of an article, a pattern carrying a predeterminedly shaded design to be duplicated in the surface of said article, a revolute support for the article mounted for swinging movement in opposite directions, yieldable means normally urging the support in one direction, a tool positioned for engagement with the article upon swinging movement of the article under the influence of said yieldable means, means opposing the action of the yieldable means to limit the extent of swinging movement of the article by the support in a direction toward the tool to provide for obtaining a predetermined depth of cut, means supporting the tool for movement toward and away from the article, and means responsive to variations in shading of the design on the pattern for moving the tool support toward and away from the article.

16. In apparatus for cutting a design in the surface of an article, a pattern carrying a predeterminedly shaded design to be duplicated in the surface of the article, a revolute support mounted for swinging movement in opposite directions, yieldable means normally urging the support in one direction, a tool positioned for engagement with the article upon movement of the support in the aforesaid direction by the yieldable means, means opposing the action of the yieldable means and effective to limit the swinging movement of the support in a direction toward the tool to provide for securing a predetermined depth of cut, a support for the tool movable in directions toward and away from the article, light sensitive means responsive to variations in shading of the design on the pattern for actuating the tool support, and means for swinging the support for the article in a direction away from said tool against the action of the yieldable means.

17. In apparatus for cutting a design in the surface of an article, a pattern carrying the design to be duplicated on the surface of the article, an optical unit for scanning the design on

the pattern including a light sensitive cell controlled by the design, a revoluble support for the pattern, a support for the optical unit, yieldable means normally urging the optical unit support in a direction toward the pattern, and means carried by the optical unit and engageable with the pattern to maintain a predetermined relationship between the optical unit and surface of the pattern irrespective of irregularities in the latter surface.

18. In apparatus for cutting a design in the surface of an article, a revoluble pattern carrying a predeterminedly shaded design to be duplicated on the surface of the article, a revoluble support for the pattern, a second revoluble support for the article, means mounting the article support for swinging movement in opposite directions, yieldable means normally urging the article support in one direction, a tool positioned for engagement with the article upon swinging movement of the article support under the influence of the yieldable means, a member carrying the tool movable toward and away from the article, an optical unit having means engageable with the 25 surface of the pattern and comprising a light sensitive cell controlled by the variations in shading of the design on the pattern, and means controlled by the light sensitive cell for actuating the tool carrying member.

30 19. In apparatus for cutting a design in the surface of an article, a revoluble drive shaft, a shaft extending transversely to the axis of the drive shaft and operatively connected thereto for rotation thereby, a support for the article secured to the second shaft for rotation therewith as a unit, a bracket member supporting the second shaft and pivotally connected to the drive shaft for swinging movement about the axis of the latter, a tool supported substantially in the 40 plane of swinging movement of the second shaft and movable toward and away from the article, yieldable means normally swinging the second shaft about the axis of the drive shaft in a direction toward the tool, means limiting the extent of swinging movement of the article toward the tool and effective to secure a predetermined depth of cut, and means for moving the tool toward and away from the article.

20. In apparatus for cutting a design in the surface of an article, a revoluble drive shaft, a second shaft extending transversely of the drive shaft and operatively connected to the latter for rotation thereby, a support for the article secured to the second shaft, a bracket member 50 supporting the second shaft and having a portion pivotally mounted on the drive shaft for swinging movement about the axis of the latter, yieldable means normally urging the second shaft in one direction about the axis of the drive shaft, a spring pressed member engageable with the article to limit the extent of swinging movement of the second shaft by the yieldable means, a tool positioned adjacent the spring pressed member and engageable with the surface of the article, means supporting the tool for movement toward and away from the article, means for actuating the tool supporting means, and means for adjusting the spring pressed member to vary the depth of cut of the tool.

70 21. In apparatus for cutting a design in the surfaces of articles, a revoluble drive shaft, a plurality of shafts extending transversely of the drive shaft in spaced relation to each other longitudinally of the latter shaft and operatively connected to said drive shaft for rotation there-

by, a support for an article secured to each of the second shafts for rotation as a unit therewith, a bracket member supporting each of the second shafts and having a portion mounted upon the drive shaft for swinging movement about the axis of the latter, a tool supported opposite each article in substantially the plane of swinging movement of the article, yieldable means for independently urging each of the second shafts about the axis of the drive shaft in a direction toward the tool, means opposing the action of the yieldable means and operable to independently position each article relative to the associated tool, means for supporting the tool for movement toward and away from the article; and means 15 for actuating the tool support.

22. In apparatus for cutting a design in the surface of an article, a pattern carrying a predeterminedly shaded design to be duplicated on the surface of the article, a tool positioned opposite the article and movable into and out of engagement therewith, an optical unit positioned opposite the pattern for scanning the design on the latter and including a light sensitive cell controlled by the shading of the design, means controlled by the light sensitive cell for moving the tool into and out of engagement with the article, a carriage forming a support for both the article and pattern, means for feeding the carriage in one direction at a predetermined rate, means 30 operating in timed relation to movement of the carriage in the last named direction to discontinue the operation of the feeding means, means permitting movement of the carriage in the opposite direction, and means operating in timed relation to return movement of the carriage in the last named direction to render the feeding means operative.

23. In apparatus for cutting a design in the surface of an article, a reciprocating carriage, a revoluble pattern mounted on the carriage and having a predeterminedly shaded design to be reproduced on the surface of the article, a revoluble support for the article mounted on the carriage, a tool mounted for movement toward and away from the article, means mounting the article support on the carriage for swinging movement toward and away from the tool, means normally urging the article in a direction toward the tool, means limiting the extent of swinging movement of the article toward the tool and effective to provide a predetermined depth of cut, and means for moving the tool toward and away from the article including an optical unit for scanning the pattern and having a photo-electric cell controlled by the variations in shading of the design on the pattern.

24. In apparatus for cutting a design in the surfaces of a plurality of articles, a reciprocable carriage, a revoluble drive shaft mounted on the carriage, a plurality of shafts extending transversely to the drive shaft and spaced from each other longitudinally of the drive shaft, means operatively connecting the second shafts to the drive shaft for rotation by the latter, a support 60 for an article secured to each of the second shafts for rotation therewith, a bracket member supporting each of the second shafts and having a portion pivotally mounted on the drive shaft for swinging movement about the axis of the latter, a tool movable into and out of engagement with each article and supported substantially in the plane of swinging movement of the article, means associated with each bracket member for independently swinging the brackets in a direction 65 70 75

toward the tools, and means for simultaneously swinging the bracket members about the axis of the drive shaft against the action of the yieldable means.

means.

25. In apparatus for cutting a design in the surfaces of a plurality of articles, a drive shaft, a plurality of shafts extending transversely to the drive shaft in spaced relation to each other longitudinally of the drive shaft and operatively connected to the latter for rotation thereby, an article support secured to each of the second shafts for rotation therewith as a unit, an additional shaft extending transversely to the drive shaft and connected to the latter for rotation thereby, a pattern secured to the additional shaft and having a predeterminedly shaded design to be duplicated on the surfaces of the articles, a bracket member supporting each of the article carrying shafts and having a portion mounted on the drive shaft for swinging movement about the axis of the latter, a tool supported opposite each article in substantially the plane of swinging movement of the articles, an optical unit supported for sliding movement toward and away from the pattern for scanning the design and having a light sensitive cell controlled by the variations in shading of the design, means controlled by the light sensitive cell for simultaneously moving the tools into and out of engagement with the articles, yieldable means urging each of the article carrying brackets in a direction toward the tools, additional means for urging the optical unit in a direction toward the pattern, and means opposing the action of the aforesaid yieldable means to maintain the articles in predetermined relationship to the tools.

26. In apparatus for cutting a design in the surface of an article, a pattern carrying the design to be duplicated on the surface of the article, a revoluble tool, a rotatable support for the article mounted for movement toward and away from the tool, traversing means for moving the article support relative to the tool in a direction transverse to the direction of movement aforesaid, yieldable means normally urging the support in a direction to engage the article with the tool, means counteracting the yieldable means and operable to predeterminedly position the article relative to the tool during movement of the article by the traversing means, a support for the tool movable toward and away from the article, an optical unit for scanning the design on the pattern including a light sensitive cell controlled by the design, and means controlled by the light sensitive cell for moving the tool support toward and away from the article.

27. In apparatus for cutting a design in the surface of an article, a pattern carrying the design to be duplicated on the surface of the article, a revoluble tool, a rotatable support for the article mounted for movement toward and away from the tool, traversing means for moving the article support relative to the tool in a direction transverse to the direction of movement aforesaid, yieldable means normally urging the support in a direction to engage the article with the tool, a feeler engageable with the article at a point adjacent the tool and supported for movement toward and away from the article, yieldable means urging said feeler into engagement with the article with a force greater than the yieldable means acting on said article support whereby the feeler positions the article relative to the tool, means movable with the article support by the traversing means to limit movement of the

feeler toward the article and operable to change the position of the feeler relative to the tool in accordance with the contour of the surface of the article to maintain a uniform depth of cut of the tool throughout the traversing movement of the article irrespective of the profile contour of the surface of the article being engraved, a support for the tool movable relative to the feeler toward and away from the article, an optical unit for scanning the design on the pattern including a light sensitive cell controlled by the design, and means controlled by the light sensitive cell for moving the tool support toward and away from the article. 5 10

28. In apparatus for cutting a design in the surface of an article, a pattern carrying the design to be duplicated on the surface of the article, means rotatably supporting the article, a variable speed motor for rotating the support at differential speeds, a tool movable toward and away from the article, an optical unit for scanning the design on the pattern including a light sensitive cell controlled by the design, means operable in timed relation to scanning of the design by the optical unit for changing the speed of said motor, and means controlled by the light sensitive cell for moving the tool toward and away from the article. 15 20 25

29. In apparatus for cutting a design in the surface of an article, a pattern carrying the design to be duplicated on the surface of the article, a tool movable toward and away from the article, means for rotatably supporting the article, means effective upon engagement of the tool with the article to rotate the article support at a relatively slow rate of speed and upon withdrawal of the tool from the article to increase the speed of rotation of the article support, an optical unit for scanning the design on the pattern including a light sensitive cell controlled by the design, and means controlled by the light sensitive cell for moving the tool toward and away from the article 30 35 40

30. In apparatus for cutting a design in the surface of an article, a pattern carrying the design to be duplicated on the surface of the article, means for rotatably supporting the article, a tool movable toward and away from the article, an optical unit for scanning the design on the pattern including a light sensitive cell for moving the tool toward and away from the article, and means operable during the intervals the design is being scanned by the optical unit to rotate the article support at a relatively slow rate of speed and operable during the intervals the plane surface of the pattern is being scanned to increase the speed of rotation of the article. 45 50 55

increase the speed of rotation of the article.

31. In apparatus for cutting a design in the surfaces of articles, means for supporting adjacent articles in spaced relation to each other, a pattern carrying the record to be duplicated on the surfaces of the articles, a revoluble shaft extending along one side of the articles, a tool positioned opposite each article and mounted on the shaft for actuation by the latter, means supporting the shaft for movement transversely of the axis thereof toward and away from the articles to effect movement of the tools into and out of engagement with the surfaces of the articles upon which the design on the pattern is to be duplicated, an optical unit for scanning the design on the pattern including a light sensitive cell controlled by the design, and means controlled by the light sensitive cell for actuating the shaft

supporting means to move the shaft and tools in directions toward and away from the articles.

32. In apparatus for producing a design in the surfaces of a plurality of articles, means for supporting the articles in spaced relation to each other, a pattern carrying the record to be duplicated on the surfaces of the articles, a tool supported opposite each article for movement toward and away from the surface of each article, an optical unit for scanning the record on the pattern including a light sensitive cell controlled by said record, and means controlled by the light sensitive cell for moving the tools as a unit into and out of engagement with the surfaces of the articles upon which the record is to be reproduced.

33. In apparatus for cutting a design in the surface of an article, a pattern carrying the record to be reproduced on the surface of the article, a revoluble tool supported for movement into and out of engagement with the article, a rotatable support for the article movable relative to the tool in a direction transverse to the direction of movement of the tool, traversing means for moving the article support relative to the tool in the last named direction, means movable with the article by the traversing means and effective to vary the relative positions of the tool and article according to variations in the profile contour of the surface of the article to maintain a substantially uniform depth of cut, an optical unit for scanning the record on the pattern including a light sensitive cell controlled by said record, and means controlled by the light sensitive cell for moving the tool support toward and away from the article.

34. In apparatus for producing a design in the surface of an article, a pattern carrying the design to be reproduced on the surface of the article, means rotatably supporting the article, means for rotating the support at differential speeds, a tool movable toward and away from the article, an optical unit for scanning the design on the pattern including a light sensitive cell controlled by the design, means controlled by the light sensitive cell for moving the tool toward and away from the article, and means revoluble with the article support and predeterminedly located with reference to the design on the surface of the article for

controlling the differential speed means to rotate the support at different speeds.

35. In apparatus for cutting a design in the surface of an article, a pattern carrying the design to be reproduced on the surface of the article, a tool supported opposite the surface of the article for movement toward and away from said surface, an optical unit for scanning the design on the pattern including a light sensitive cell controlled by the design, means controlled by the light sensitive cell for moving the tool toward and away from the article, and means controlled by the surface of the article for adjusting the position of the article relative to the tool in accordance with variations in the profile contour of the surface to maintain a uniform depth of cut of the tool in the article irrespective of variations in the surface contour of the article.

36. In apparatus for cutting a design in the surface of an article, a pattern carrying the design to be duplicated on the surface of the article, a revoluble tool, a rotatable support for the article mounted for movement toward and away from the tool, yieldable means normally urging the article support in a direction to engage the article with the tool, means counteracting the yieldable means and effective to maintain substantially the same relationship between the tool and article irrespective of variations in the profile contour of the article, an optical unit for scanning the design on the pattern including a light sensitive cell controlled by the design, and means controlled by the light sensitive cell for moving the tool toward and away from the article.

37. In apparatus for producing a design in the surfaces of a plurality of articles, means for supporting the articles in spaced relation to each other, a pattern carrying a record to be duplicated on the surface of each article, a tool supported opposite each article, an optical unit for scanning the record on the pattern including a light sensitive cell controlled by the record, and means controlled by the light sensitive cell for relatively moving the tools as a unit and articles as a unit toward and away from each other to provide for reproducing the record on each of the articles.

EVERETT J. COOK.
